(57) **CLAIM**

I claim the ornamental design for a hand-held atomizer, substantially as shown and described.

DESCRIPTION

FIG. 1 is a front elevation view of a hand-held atomizer; FIG. 2 is a left side elevation view of a hand-held atomizer; FIG. 3 is a right side elevation view of the hand-held atomizer;

FIG. 4 is a back elevation of the hand-held atomizer;

FIG. 5 is a top plan view of the hand-held atomizer; FIG. 6 is a bottom plan view of the hand-held atomizer; and, FIG. 7 is top, front, perspective view of the hand-held atomizer.

The broken lines in the drawings depict portions of the hand-held atomizer that form no part of the claimed design.
